R. M. HENDERSON.
CABINET FOR HOLDING STATIONERY.
APPLICATION FILED APR. 22, 1914.

1,143,391.

Patented June 15, 1915.

UNITED STATES PATENT OFFICE.

RALPH M. HENDERSON, OF TOLEDO, OHIO.

CABINET FOR HOLDING STATIONERY.

1,143,391.

Specification of Letters Patent.

Patented June 15, 1915.

Application filed April 22, 1914. Serial No. 833,698.

To all whom it may concern:

Be it known that I, RALPH M. HENDERSON, a citizen of the United States, residing at Toledo, in the county of Lucas, State of Ohio, have invented certain new and useful Improvements in Cabinets for Holding Stationery; and I do hereby declare the following to be a full, clear, and exact description of the invention, such as will enable others skilled in the art to which it appertains to make and use the same.

The present invention is directed to cabinets for holding stationery, and has for its object to so construct a device of this character that one sheet of paper or an envelop may be fed therefrom at a time.

A further object of the invention is to provide a cabinet of this type having combined therewith a frame for displaying cards with advertising matter printed thereon.

A still further object of the invention is to provide a device of this character particularly adapted for use upon writing tables in hotels.

With these and other objects in view, this invention resides in the novel features of construction, formation, combination and arrangement of parts to be hereinafter more fully described, claimed and illustrated in the accompanying drawing, in which:—

Figure 1 is a front elevation of the device. Fig. 2 is a section on line 3—3 of Fig. 1. Fig. 3 is a top plan view. Fig. 4 is a similar view on line 4—4 of Fig. 2. Fig. 5 is a similar view on line 5—5 of Fig. 1. Fig. 6 is a detail perspective view of one of the actuating shafts.

Referring to the drawing, the numeral 1 designates a base, the same being provided with feet 2, and a supplemental base 3 designed for holding an ink well 4. Supported upon the base is a casing 5, said casing being divided into compartments 6 and 7 by a vertical partition 8. The compartment 6 is of greater dimensions than the compartment 7 and is designed for holding sheets of writing paper, while the compartment 7 receives envelops, which are placed therein end-wise.

Rotatably supported by the end walls 9, and partition 8 is a shaft 10, one end of which projects beyond one of the end walls and is provided with a handle 11 which when grasped serves to rotate said shaft. The shaft extends longitudinally of the cas-

ing and has that portion which is located in the compartment 6 provided with a plurality of spaced disks 12, which are preferably formed from metal and each having a groove formed in its periphery in which is mounted a rubber band 12' containing grit so as to more effectually force the paper upward, a sheet at a time so that one edge of a sheet will project through the longitudinal slot 13 formed in the removable top 14.

The shaft for forcing paper out of the cabinet is provided with three disks while the shaft for forcing the envelops out is provided with two disks. In order that the disks may be rotated to force the paper out and may then be disengaged from the paper, I have provided the following construction: The shaft 10 is rotatably and slidably supported in an elongated horizontal slot 16 in each side wall of the casing 5. The shaft is yieldingly held in the forward portion of this slot and the disks out of contact with the paper by the spring 17 which is secured to each side wall. Fixedly mounted on the shaft 10 at each end thereof is a wheel 15' substantially circular, but having a notch 16' therein and a cam surface 17' leading therefrom. Riveted to each side of the casing is a stud 17" which normally is in engagement with the circular portion of the wheel when the disks are in engagement with the paper, but which is adapted to engage in the notch 16'. Assuming that the disks 12 are in contact with the paper and the device is ready to be operated, the shaft is rotated counter-clockwise by turning the handle 11. The circular portion of the wheel 15' is held into engagement with the stud 17" by the spring 17 and rides thereon. As the shaft 10 is rotated the notch 16' approaches the stud and the stud drops into said notch, this allows the spring 17 to act to throw the shaft 10 to the forward part of the slot and the disks out of engagement with the paper so that the same can be withdrawn from the cabinet. To repeat the operation it is only necessary to continue the counter-clockwise movement of the shaft 10 and the cam surface 17' rides on the stud, thus moving the shaft to the rear of the slot against the action of the spring, and the disks into engagement with the paper.

A similarly constructed shaft 18 is provided, and is mounted for operation in the compartment 7 for ejecting envelops therefrom.

through the slot 19 also formed in the cover 14 and in alinement with the slot 13. Mounted in the compartments 6 and 7 are vertically disposed plates 20, which are forced 5 toward the front of the casing 5 by coil springs 21 which are interposed between said plates and the back wall 22 of the casing, said plates serving to advance an envelop or sheet of paper one at a time so as to be 10 in proper position to their respective slot. Mounted in each of the compartments 6 and 7 and to the rear of the disks 12 is a plate 20' which has in its upper end spaced slots 21' through which the disks 12 project and 15 into contact with the paper or envelops as the case may be. Secured to the front wall 17 of the casing 5 is a frame 23, said frame being provided with a plurality of supplemental racks 24 for interchangeably receiving 20 advertising cards 25. To protect the advertising cards a glass pane 26 is provided and covers the racks 24. The compartments 6 and 7 have removably mounted therein 25 blocks 27 and 28, respectively which may be interchanged so as to properly position envelops or sheets of paper of different sizes in the compartments.

What is claimed is:—

1. A stationery dispensing cabinet comprising a rectangular casing, a dividing wall in said casing, a vertically extending wall on each side of said dividing wall and hav- 30

ing a plurality of slots therein, means for maintaining sheets of paper in contact with said vertical wall, a shaft rotatably mounted 35 to one side of said vertical wall, a plurality of resilient wheels on said shaft, means to rotate the said wheels and simultaneously project the same through the aforementioned slots to engage the adjacent sheet of 40 paper, and means to automatically retract said wheels.

2. In a stationery dispensing cabinet, a plurality of compartments, a vertical wall in each of said compartments, said wall having a plurality of spaced slots therein, the said compartments being adapted to contain paper, means to cause the paper to engage the said vertical walls, a shaft located in each of said compartments and having a plurality of wheels thereon adapted to project through the said slots to engage the adjacent sheet of paper, a cam at each end of each of said slots, pins adapted to coöperate with 45 said cam to cause the same to move into said slots upon the rotation of the shaft, and resilient means for retracting the said wheels. 50

In testimony whereof, I affix my signature, in the presence of two witnesses.

RALPH M. HENDERSON.

Corrections in Letters Patent No. 1,146,391

It is hereby certified that in Letters Patent No. 1,146,391, granted July 13, 1915, upon the application of Jonas W. Aylsworth, of East Orange, New Jersey, for an improvement in "Methods of Forming Molded Articles," errors appear in the printed specification requiring correction as follows: Page 3, line 33, for the word "resin" read *rosin*; page 4, line 30, after the word "pressing" insert the article *a*; page 5, line 27, strike out the word "which," second occurrence; and that the said Letters Patent should be read with these corrections therein that the same may conform to the record of the case in the Patent Office.

Signed and sealed this 28th day of September, A. D., 1915.

[SEAL.]

J. T. NEWTON,

Acting Commissioner of Patents.
